UNITED STATES PATENT OFFICE

166,530

MOBILE REPAIR SHOP

Kibbey W. Couse, Newark, N. J.

Application September 13, 1951, Serial No. 16,626

Term of patent 14 years

(Cl. D14—4.8)

To all whom it may concern:

Be it known that I, Kibbey W. Couse, a citizen of the United States of America and a resident of Newark, in the county of Essex and State of New Jersey, have invented a new, original, and ornamental Design for a Mobile Repair Shop, of which the following is a specification, reference being had to the accompanying drawing, forming a part thereof.

Figure 1 is a side elevational view of a mobile repair shop, showing my new design;

Figure 2 is a perspective view of the repair shop from the front and the side thereof shown in Figure 1;

Figure 3 is a perspective view from the rear and the side of the mobile repair shop opposite that located in Figure 1;

Figure 4 is a perspective view from the rear and the side of the mobile repair shop as illustrated in Figure 3, showing portions in open position and other portions in unfolded or extended position; and

Figure 5 is a perspective view from the rear and the side of the mobile repair shop illustrated in Figure 1 with portions in open position and other portions in unfolded or extended positions.

The dominant features of the design are illustrated by solid lines.

I claim:

The ornamental design for a mobile repair shop, as shown and described.

KIBBEY W. COUSE.
